UNITED STATES PATENT OFFICE.

RUDOLF WASSERMAN, OF NEW YORK, N. Y.

MARKING DEVICE.

Application filed June 18, 1926. Serial No. 116,921.

This invention relates to marking devices, adapted to contain powder or any other granular material, which is ejected by a plunger bar 4, the latter mounted to move through an opening 5 in an angle bracket 28. This angle bracket 28 is secured to the bar 1 by screws or other securing means 29, and the opening 5 functions as a guide through which the bar 4 is movable, as will more fully hereinafter appear.

I have illustrated and shall describe my invention as a marker for skirts so as to enable the operator while wearing the skirt to evenly mark on the same a line or series of marks indicating a predetermined distance from the floor so that the skirt may be folded and shaped evenly to give the desired length. It is to be understood, that the invention is not restricted to any particular use as I desire to cover the same broadly for any use to which it can be put.

A further object is to provide a device of this character which can be manufactured and sold at a reasonably low price, and which can be readily assembled by any one of average training not requiring skilled labor.

25 A further object is to provide a device of this character which is extremely simple in construction, not liable to get out of repair, and which will most efficiently perform the functions for which it is intended.

30 With these and other objects in view, the invention consists in certain novel features of construction and combinations and arrangements of parts, which will be more fully hereinafter described and pointed out in the claims.

In the accompanying drawings—

Figure 1 is a perspective view showing my improved device in operative position as a skirt marker;

40 Figure 2 is a broken view in elevation;

Figure 3 is a view mainly in side elevation but partly broken away and partly in section;

45 Figure 4 is a view in transverse section on the line 4—4 of Figure 3;

Figure 5 is an upper face view of the bottom plate of the powder receptacle.

50 1 represents a bar which may be of wood or any other suitable material, and which has on one face, preferably its outer face, a linear scale 2'. On this bar 1 a receptacle 2 is adjustably secured so that it may be positioned at any desired distance from the end of the bar 1. This receptacle is

55 60 65 70 75 80 85 90 95 100 105

granular material, which is ejected by a plunger bar 4, the latter mounted to move through an opening 5 in an angle bracket 28. This angle bracket 28 is secured to the bar 1 by screws or other securing means 29, and the opening 5 functions as a guide through which the bar 4 is movable, as will more fully hereinafter appear.

The receptacle 2 is of somewhat inverted cup shape and has a top closure plate 6 and a bottom closure plate 7. The top closure plate is made with a curved end 8 adapted to fit under a curved bead 9. It will be noted that the curved end 8 and the bead 9 are greater than a semicircle so that in assembling the parts it is necessary to project the head 8 into the open upper end of receptacle 2 and then turn the plate horizontally so as to bring it within the confines of the bead 9 and form a closure therefor, without other securing means. This head 8 has an opening 10 through which the plunger bar 4 projects.

The plate 6 constitutes a fixed part of a bifurcated U-shaped guide member 11. The bifurcations of this member 11 have aligned openings 12 which receive the scale bar 1, and a set screw 13, mounted in the intermediate portion of the guide member 11, is adapted to be jammed against the edge of the scale bar 1 and secure the receptacle 2 at the desired position on said scale bar.

The bottom plate 7 of receptacle 2 is shown in top plan in Figure 5. This plate is of general circular form and is secured to the bottom of receptacle 2 by bending the edges of said receptacle over the bottom plate 7, as shown at 14, so as to make a tight joint between the parts. This bottom plate 7 has an internally screw-threaded nipple 15 constituting an entrance for powder, indicated by reference numeral 16. A screw plug 17 is normally screwed into this nipple 15 and serves as a closure therefor and can be conveniently removed and a new supply of powder directed into the receptacle when the latter is in an inverted position.

I would call particular attention to the contour of this bottom plate 7, shown in Figure 5, in which it will be noted that an extension 18 is provided on this plate and this extension has a transversely extending depression 19 adjacent its outer edge which

is connected by a relatively narrow passage 20 with a central circular depression 21 in plate 7.

The receptacle 2 above referred to has an extension 22 thereon which corresponds in shape, that is, in plan with that of the extension 18 so that these two extensions form a nozzle 23 through which the powder is discharged.

10 The extension 22 has a transversely extending recess 24 in its underface located above the depression 19, this depression raising the material of the extension so that in plan an upwardly projecting transverse bead 15 25 is formed.

At the extremity of the extension 22, the metal is upwardly offset, as shown at 26, so that a narrow outlet of approximately the full length of the width of the extension is 20 provided, through which the powder is ejected to form a line or mark wherever desired.

An important feature of my invention is the provision of an inverted semi-spherical resilient cup 27 within the receptacle 2. 25 This cup 27 is preferably of rubber and constitutes an ejector and fits within the receptacle, as clearly shown in Figure 3, and constitutes an enclosure for powder 16.

The lower edges of this ejector cup 27 30 rest upon the bottom 7, and the lower end of the plunger bar 4 rests upon the top of this plunger cup, so that when the bar 4 is given a downward movement the powder 4 16 will be ejected through the nozzle 23, and when the pressure is relieved on the bar 4 35 the cup 27 will expand to its normal position.

This cup 27 is of such material that it 40 can be folded and inserted through the open top of the receptacle 2 when the plate 8 is uncoupled, so that all the parts above described can be readily assembled and can be easily taken apart when it is desired to repair or substitute parts.

45 The operation is as follows:

Assuming that the device is to be used as a skirt marker, attention is directed to Figure 1, wherein it will be seen that receptacle 2 is adjusted or secured on the scale bar 1 50 at the desired distance from the free end of this bar, which is adapted to rest upon the floor. The operator grasps the plunger bar 4 and positions the nozzle 23 against or adjacent the skirt. By imparting a downward push or movement to the bar 4, the rubber cup 27 is compressed and the powder 16 is forced through the nozzle 23 to make a mark on the skirt as clearly shown.

55 While I refer to the material 16 as powder it is understood that I may use any granular material of any desired color.

Various slight changes and alterations might be made in the general form of the parts described without departing from my invention, and hence I do not limit myself

to the precise details set forth but consider myself at liberty to make such slight changes and alterations as fairly fall within the spirit and scope of the appended claims.

70 I claim:

1. A marking device, including a scale bar, a receptacle adjustably secured on the scale bar and adapted to contain powder, said receptacle having an outlet therefrom, an inverted resilient cup in the receptacle, 75 and means for compressing the cup to discharge the powder.

2. A device of the character described, comprising a scale bar, a powder receptacle adjustable on the scale bar, an inverted rubber cup ejector in the receptacle, and a plunger bar engaging the cup. 80

3. A device of the character described, comprising a scale bar, a powder receptacle adjustable on the scale bar, an inverted rubber cup ejector in the receptacle, a plunger bar engaging the cup, and a bracket on the scale bar holding the plunger bar substantially parallel with said scale bar. 85

4. A device of the character described, comprising a scale bar, a bracket on the scale bar constituting a guide, a plunger bar movable through the guide bracket, a powder receptacle adjustable on the scale bar and having an opening in its top receiving the plunger bar, an inverted semi-spherical resilient cup in the receptacle on top of which the plunger rests, said cup adapted to receive powder thereunder and said cup having a nozzle thereon through which powder is ejected when the cup is compressed by the plunger bar. 95

5. In a device of the character described, including a scale bar, a plunger bar mounted to move parallel therewith, a powder receptacle, a bifurcated member secured to the receptacle and having openings therein receiving the scale bar, a set screw in the guide member adapted to engage the scale bar and secure the receptacle at any desired adjustment on the scale bar, said receptacle having an opening in its top to receive the plunger bar, a nozzle on the receptacle, and an inverted flexible ejector cup in the receptacle engaged by the plunger bar and adapted to force the portion of the contents of the receptacle through the nozzle at each movement of the plunger bar in one direction. 105

6. A marking device including a receptacle, having a substantially circular opening in its top and an annular bead around said opening, a plate having a curved end adapted to fit under the bead and close the top of the receptacle, said bead and curved end of the plate forming an arc greater than a semicircle, a bifurcated guide constituting an integral part of said plate, a scale bar receiving the guide, means for securing the guide at any adjustment on the scale bar, a 110

125

130

plunger bar projecting through the first-mentioned plate into the receptacle, a nozzle on the receptacle, and means in the receptacle operated by the plunger bar for ejecting the contents of the receptacle.

7. A device of the character described, comprising a receptacle, a bottom plate on the receptacle having an extension thereon, said bottom plate and said extension having

depressions therein connected by a narrow 10 passage, an extension on the receptacle above the extension on the bottom plate whereby a nozzle is formed, means for securing said receptacle adjustably to a scale bar, and means for ejecting the contents of said receptacle through said nozzle. 15

RUDOLF WASSERMAN.
